Application June 13, 1956, Serial No. 591,170

2 Claims. (Cl. 20—91)

The present invention relates to doors, more particularly to improvements in composite type flush doors and the invention has for a principal object the provision of a new and improved composite type flush door, which is attractive in appearance, sturdy in construction, will not warp, and may be assembled by quantity production techniques.

Another object of the present invention is to provide a composite type door which includes peripheral edge trim members which enhance the appearance of the door and which protect the door against warping.

Still another object of the present invention is to provide a door including peripheral edge trim members which may be readily and accurately positioned about the marginal edges of the door.

A yet further object of the present invention is to provide an improved edge trim member for enhancing the appearance of a door associated therewith and for bracing the door to prevent warping thereof.

Briefly, the above and further objects are realized in accordance with the present invention by providing a door which comprises a frame covered by suitable coverings and a peripheral metallic trim and brace which protects the edges of the door and prevents warping. The door frame is provided with a peripheral groove in the marginal edge thereof for receiving a positioning web of the edge trim strips which are positioned around all of the edges of the door.

The invention, both as to its organization and method of operation, together with further objects and advantages thereof, will best be understood by reference to the following detailed description taken in connection with the accompanying drawing, in which:

Fig. 1 is a partially sectioned perspective view of a door constructed in accordance with the present invention;

Fig. 2 is a fragmentary view of the door of Fig. 1, taken along the line 2—2 thereof;

Fig. 3 is a fragmentary enlarged cross-sectional perspective view of the edge trim member of the present invention; and

Fig. 4 is a sectional view taken along the line 4—4 of Fig. 1 and shows a hinge plate attached to the door of Fig. 1.

Referring now to the drawings, and particularly to Figs. 1 and 2 thereof, the composite type flush door of the present invention is indicated as a whole by reference character 10. It comprises a rectangular frame formed of a plurality of upright frame members 12 and a plurality of end frame members 14, the corner joints between the frame members 12 and 14 being conventional and forming no part of the present invention. The frame members 12 and 14 and, if necessary, any cross-brace members which may be positioned intermediate the end members 14 are preferably constructed of wood and prior to the assembly of the frame, one edge of each of the frame members 12 and 14 is provided with a full length groove 12a and 14a so that in the final construction a peripheral

2

groove is provided in the marginal edges of the door frame.

As shown, a honeycomb core 16 or any other suitable core material may be disposed within the space between the frame members 12 and 14. The thickness of the core material 16 is substantially equal to and no greater than the thickness of the door frame and provides a primary structural element against which a plurality of flat panels 18 and 20 are positioned in an unwarped condition. The panels 18 and 20 each have a height and width equal to that of the door frame so that the edges of the panels 18 and 20 lie flush with the outer edges of the frame members 12 and 14. The panels 18 and 20 may be constructed of any suitable material such as, for example, plywood, but fiber board or hard board is preferable because of its high strength and low cost as compared to plywood.

In order to provide an attractive, decorative door which may be made available for use with a number of long lasting finishes of different colors requiring practically no maintenance other than an occasional cleaning, the panels 18 and 20 are covered with plastic covering skins or sheets 22 and 24 secured by suitable means, such as cementing, to the outer surfaces of the panels 18 and 20. As best shown in Fig. 2, the edges 22a and 24a of the plastic sheets partially overlap the marginal edges of the door frame, terminating intermediate the grooves 12a and 14a and the junction of the panels 18 and 20 and the door frame. It will be understood that although the invention is particularly advantageous for use with a door having covering skins 22 and 24 made of plastic, it also finds utility when used in connection with a door having a metallic covering. Accordingly, the skins 22 and 24 may, if desired, be formed of thin metallic sheets.

In order to protect the edges of the coverings 22 and 24 at the edges of the door and also in order to enhance the appearance of the overall door construction by providing a metallic border therefor, a plurality of edge trim strips 26 are secured to all four edges of the door frame over the overlapping portions of the plastic sheets 22 and 24. The four-edge trim strips 26 are identical, being preferably extruded from aluminum or other suitable material. Since it is desirable that the trim strips 26 engage the sheets 22 and 24 in the immediate vicinity of the faces of the door 10, recesses 28 and 29 are provided in the face of the trim members 26 so as to define a pair of beads 36 which extend along the opposite sides of the trim strip 26. Moreover, the grooves 12a and 14a are deeper than the height of the web 30 on the trim strip 26 so that the webs 30 do not bottom in the grooves 12a or 14a when the trim strips 26 are assembled to the door frame. Accordingly, when the trim strips 26 are assembled to the door and attached to the frame members 12 and 14 by a plurality of wood screws 32 which extend through suitable apertures 34 in the trim strips 26, the beads 36 engage the sheets 22 and 24 opposite the edges of the panels 18 and 20 near the faces of the door. As best shown in Figs. 2 and 3, the outwardly directed edges 36a of the beads 36 are chamfered so that any irregularities which may be present along the edges of the door between the sheets 22 and 24 and the trim strip 26 are not visually apparent.

It may thus be seen that the centrally disposed web 30 on the edge trim member 26 acting in cooperation with the central grooves 12a and 14a provided in the frame members facilitates positioning of the edge trim strips 26 on the door and, moreover, assures that the trim strips 26 are accurately positioned even if the door is assembled by relatively unskilled labor. In addition to facilitating the attaching of the edge trim member 26 to the door frame, the web 30 provides a light stop which prevents the passage of light between the door frame and the trim

member 26. Consequently, if the edges of the door frame are not perfectly straight, such irregularities are not apparent to one observing the door, and of course, the door is light-tight.

For the purpose of securing hinges, door locks and other hardware on the door 10, portions of the trim strip 26 may be cut away. Referring particularly to Fig. 4, it may be seen that a hinge plate 40 is positioned in the cut-away portion of the trim strip 26 and screwed to the door. Moreover, the plate 40 may include a web for reception in the groove 12a to facilitate accurate positioning of the hinge 40 on the door frame, thereby simplifying the installation of the door.

The present invention thus enables a door 10 which is particularly suited for interior use in buildings, homes, etc., and has the important advantage over the interior doors known in the prior art that it may be provided in a wide variety of colors or metallic finishes and may be completely prefabricated and assembled at the factory, no alterations, or painting being necessary when the door is installed.

Accordingly, since the door 10 is completely fabricated and finished at the factory, since it cannot warp, and since it is relatively low in weight, the cost of manufacture, upkeep, transportation and installation are greatly reduced over that of interior doors of the prior art type. Furthermore, by using one of the new type plastics which have become commercially available in the past few years, such, for example, as vinyl, the finish on the doors 10 is extremely tough and durable and the doors 10 thus maintain their attractive appearance for many years.

While the invention has been described in connection with a particular embodiment of the invention, it will be understood that various modifications may be made thereon which are within the true spirit and scope of the invention as defined in the appended claims.

What is claimed as new and desired to be secured by Letters Patent of the United States is:

1. A composite flush door comprising, a rectangular frame formed of a cellulosic material and having a peripheral groove in and extending the entire length of the marginal edges thereof, a pair of rigid panels secured over opposite sides of said frame with the edges of said panels lying flush with the edges of the frame, a honey-

comb filler material disposed within the space defined by said frame and said panels, a plurality of thin plastic sheets covering the exterior sides of said panels and partially overlapping the marginal edges of said frame, a plurality of metallic edge trim strips secured to said frame over the marginal edges thereof to provide a metallic border for said door, the widths of said strips being substantially equal to the combined thicknesses of said frame, said panels and the two covering sheets, an inwardly directed web on each of said strips which extend throughout the length thereof, said webs being positioned in said groove, the height of said webs being less than the depth of said groove, and a pair of longitudinal beads disposed near the edges of said trim strips engaging said plastic sheets only in the area adjacent to the ends of said panels.

2. A door comprising a frame formed of a plurality of uprights and a plurality of end members, a pair of rigid panels secured over opposite sides of said frame and having edges flush with the edges of the frame, a plurality of plastic covering sheets disposed over opposite sides of said door frame and at least partially overlapping the marginal edges of said frame, said uprights and end members having longitudinal grooves in the marginal edges thereof thereby to provide a substantially peripheral groove in the marginal edges of said frame, and a plurality of edge trim members positioned over the marginal edges of said frame and substantially covering the overlapping portions of said skins, each of said trim members having a longitudinal web which is positioned in said groove, the width of said members being substantially equal to the width of the door, said trim members being in engagement with only that part of the overlapping portions of the skins which are adjacent to the edges of the door frame.
